SHORTS

Jacob A. Goldfarb, Frankfort, and Everett J. Moore, Bowling Green, Ky., assignors to Union Underwear Co., Inc., Frankfort, Ky., a corporation of Kentucky

Application May 1, 1944, Serial No. 533,482

2 Claims. (Cl. 2—224)

This invention relates to an undergarment and particularly to shorts, having for a primary object the incorporation of means therein for the utmost comfort by maintaining fit with ample elasticity, all by a minimum number of parts readily and relatively cheaply produced and assembled.

Other important objects and advantages of the invention will become apparent to those versed in the art in the following description of one particular form as illustrated in the accompanying drawings, in which

Fig. 1 is a view in rear elevation of a garment embodying the invention;

Fig. 2, a view in front elevation with the right hand leg of the garment raised to a horizontally disposed position;

Fig. 3, a view in disassembled relation of parts forming the garment belt; and

Fig. 4, a view in disassembled relation of the parts forming the garment and to be attached to the belt of Fig. 3.

Like characters of reference indicate like parts throughout the several views in the drawings.

Referring to Fig. 4, two main sections 10 and 11 are formed to have the same dimensions and contour, and are made out of woven fabric having substantially no elasticity in any direction. Since both pieces 10 and 11 are identical, the description of one piece, such as piece 10, will be sufficient to describe both. It is understood, however, that the pieces 10 and 11 are in effect left and right pieces respectively. Referring to the piece 10, the lower edge AB will, upon being hemmed, be the major part of the lower end of the left leg section of the garment. The line AC will represent substantially half the length of a hem extending across the crotch of the garment. While the remainder of that edge portion, CD, will be the distance from that hem up to the underside of the front belt piece 12, Fig. 3. Then from the point D, the section has an upper edge directed upwardly in a curved manner to follow the contour of the lower line of the belt piece 12, and from the end of that piece 12, this top edge of the piece 10 continues in a straight line diverging upwardly slightly to terminate at the point E, inclining from a parallel line in reference to the lower edge AB. Between the points B and E, the piece 10 is defined by a straight edge.

A central panel 13 is formed out of a knitted material having a high degree of elasticity in horizontally disposed directions and a lesser degree of elasticity in vertically disposed directions. For example, in the case of one particular piece

of knitted material made of cotton only, the vertical stretch of the panel 13 for its entire length for a given force would be approximately one inch in comparison to a stretch through the major width of the panel under the same force of about two inches. This panel 13 is generally triangularly shaped to have a side edge FG equal to the edge EB of the piece 10, and a side edge HJ equal to the edge EB of the piece 11. The top edge of the panel 13 is defined by the short line FH being reduced to approximately $1\frac{1}{4}$ inches on the finished garment. The lower end of the panel 13 is defined by the lines GK and JL sloping inwardly and downwardly respectively from the points G and J to connect with the line KL parallel to the top line FH.

Referring to Fig. 3, the left hand front belt, section 12, is matched by a corresponding right hand belt, section 14, and these two sections 12 and 14 are in the finished garment inter-connected by their rearwardly disposed narrow ends 20 and 15 consisting, in the present form, of a woven fabric material stitched to have parallel top and bottom edges. Both the front belt sections 12 and 14 are likewise made of woven fabric material. The finished belt to all intents and purpose is one continuous line and substantially non-stretchable. To provide for variations in the length of the finished belt, eyes 30 or slots 17 are provided in the adjacent ends of the respective belt portions, through which openings a ribbon 18 may be inserted to reduce the effective length, all in the well known and usual manner.

35 In forming the garment, the panel 13 is stitched along its edges FG and HJ to the respective edges EB of the two sections 10 and 11. The combined lengths of the lines ABGK and ABJL form the respective hem lines of the lower ends of the legs 40 of the garment. Each of the sections 10 and 11 is slit from the point C to the point M, and the portions of the edges DC above the line CM are folded back to form the hems of the fly opening of the garment. The edge CM is folded downwardly along some line, such as indicated by the dash line thereunder and the outer edge (shortened) CA is stitched along the line KL with the point A being matched with the point K in the section 10, and the point A of section 11 being 45 matched with the point L. The combined lengths of those edges CA of the two sections 10 and 11 will cause the points C in each instance in their turned down condition to overlap centrally of the line KL as indicated at 18, Fig. 2. This line KL 50 then comes within the hem extending through

the crotch of the garment as indicated in Figs. 1 and 2. The upper edges of the pieces 10, 11, and 13 are stitched along the lower edges of the combined belt sections 12, 14, and 15, to complete the garment, it being understood, of course, that the ends are stitched in the usual and well known manner to cover up raw edges and the like. The ends of the belt sections 12 and 14 are provided with complementary fasteners herein indicated as the customary glove fasteners. Buttons, of course, may be provided if desired along the matching edges of the fly opening down the front of the garment.

By use of the elastic panel 13, in the manner described, it is to be seen that this panel being attached at its top end by a relatively narrow width to the belt extends downwardly in gradually increasing width entirely around and up to the hem of the crotch which hem in effect is positioned forwardly of and upwardly from the transverse median line thereof. Moreover this panel 13 has a portion entering into the leg portion to impart an elasticity to that opening, limited in effect by the edge portions GK and JL being hemmed whereby the stitching of the hem prevents undue stretching of the panel material. Thus the elasticity of this panel is provided to be at its maximum through the seat portion of the garment and yet held within control by reason of its shape and its attachment not only to the belt but also throughout the entire vertical dimension of the sections forming the leg parts of the garment.

While reference has been made above to a cotton knitted material for the panel 13, the composition of the material is not necessarily limited thereto, since the essential characteristic is one of elasticity rather than the limitation of use of cotton, wool, rubber, and synthetic rubber, and the like. It is desired however, to have a limited elasticity in the vertical direction with a considerable degree of elasticity provided in the horizontal direction.

While the invention has herein been shown and described in the one precise form, it is obvious that structural changes may be embodied, particularly in the construction of the fabric portions of the garment, and it is, therefore emphasized that the invention is not to be limited to that precise form beyond the limitations as may be imposed by the following claims.

We claim:

1. An undergarment comprising a pair of right and left leg woven fabric portions, each substantially trapezium shaped; a belt, to which the top ends of said portions are attached; a knitted fabric back panel having its upper end attached to

said belt and spacing apart said portions at said belt, said panel having straight side edges attached to opposing rear straight edges of said leg portions, and having a vertical length extending beyond that of said rear edges, said extended length sloping inwardly on each side to have a straight line edge therebetween substantially parallel to said upper panel end; the lower edges of each of said leg portions plus the adjacent sloping edge of said panel forming the lower marginal opening of a leg of the undergarment, whereby a length of the knitted fabric is included in the marginal edge with the woven fabric; said straight line of the extended portion of the knitted panel being joined one half to an equal length extending upwardly from said leg opening of the straight edge opposite said rear edge of one leg portion, and the other half to a corresponding edge of the other leg portion to form an arcuate juncture line parallel to and forwardly and upwardly of the central transverse median line of the crotch of the undergarment.

2. An undergarment comprising a pair of right and left leg woven fabric portions, each substantially trapezium shaped, a belt, to which the top ends of said portions are attached; a knitted fabric back panel having its upper end attached to said belt and spacing apart said portions at said belt, said panel having straight side edges attached to opposing rear straight edges of said leg portions, and having a vertical length extending beyond that of said rear edges, said extended length sloping inwardly on each side to have a straight line edge therebetween substantially parallel to said upper panel end; the lower edges of each of said leg portions plus the adjacent sloping edge of said panel forming the lower marginal opening of a leg of the undergarment, whereby a length of the knitted fabric is included in the marginal edge with the woven fabric; said straight line of the extended portion of the knitted panel being joined one half to an equal length extending upwardly from said leg opening of the straight edge opposite said rear edge of one leg portion, and the other half to a corresponding edge of the other leg portion to form an arcuate juncture line parallel to and forwardly and upwardly of the central transverse median line of the crotch of the undergarment; the length of the knitted fabric in said leg opening marginal being stitched to limit stretch thereof; and the balance of the lengths of the edges of said leg portions extending upwardly from said juncture line to said belt.

JACOB A. GOLDFARB.
EVERETT J. MOORE.
